AUTOMATIC DELUGE SPRINKLER SYSTEM

Harry N. Rider, Youngstown, Ohio, assignor to
"Automatic" Sprinkler Company of America,
Youngstown, Ohio, a corporation of Delaware

Application April 28, 1942, Serial No. 440,781

3 Claims. (Cl. 169—17)

This invention relates to improvements in automatic deluge sprinkler systems.

The principal object of the invention is the provision of a deluge system capable of wide application so that it can be installed in any type of structure and particularly such structures as may house hazardous occupancies including paint shops, power plants, arsenals, airplane manufacturing plants as well as airplane hangars, and which deluge sprinkler system will operate satisfactorily under any and all conditions.

A further object of the invention is the provision of an automatic deluge sprinkler system which will require a minimum of attention and wherein the component parts of the system are so designed and arranged as to be capable of withstanding all ordinary treatment to which the system may be exposed.

A still further object of the invention is the provision of an automatic deluge sprinkler system incorporating a system of heat actuated devices located in the fire zones which heat actuated devices serve to actuate the sprinkler system immediately upon the out-break of a fire.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawings, wherein:

Figure 1 is an elevational view illustrating the automatic deluge sprinkler system, the subject of this invention.

Figure 2 is an elevational view, partially in cross section, of the main fluid supply valve and actuating devices therefor.

Figure 3 is a cross sectional side elevation taken on lines 3—3 of Figure 2.

Figure 4 is a cross sectional side elevation of a modified form of the main fluid supply valve and particularly as concerns the actuating device therefor.

By referring to Figure 1 of the drawings, it will be seen that an automatic deluge sprinkler system including certain essential component parts has been illustrated and wherein the fluid supply for supplying fire extinguishing fluid water pressure takes the form of a fluid supply

pipe 15 which is provided with a manually operated gate valve 16 which is normally open and thus brings the fluid supply source into direct communication with an automatically operated main valve 17 which controls the entrance of a fire extinguishing fluid into a riser 18 and various distributing pipes 19 which may and will obviously lead to the various fire zones to be protected, as well as to water curtain installations covering and protecting indicated areas. The pipes 19 and such branch pipes as may be necessary are supplied with normally open sprinklers 20 which may be of any of the conventional types known in the art. The main control valve 17 is automatically actuated and so designed that a clapper therein is held closed at such time as the system is not in operation. An activating device, generally indicated at 21, includes means for unlatching the clapper of the valve 17 and therefore forms a component part of the valve 17, the actuating device 21 forming a terminal for a plurality of heat actuated devices 22 which are thermally sensitive devices and which communicate with the actuating device 21 by means of pneumatic impulse conducting tubing 23. The heat actuated devices 22 are located in spaced relation to one another in the various fire zones or other areas in which the various open sprinklers 20 are located. In order to maintain supervision of the heat actuated devices 22 and their pneumatic impulse conducting tubing 23, air under relatively low pressure is maintained in the tubing 23 and the heat actuated devices 22 as well as in the connecting portions of the actuating device 21, the said air pressure being supplied by an air pump and alarm unit, generally indicated at 24 which unit is supplied with water under pressure through a supply pipe 25 which communicates with the main supply pipe 15, a filter 26 is positioned in the pipe 25 to insure the delivery of clean water to the air pump and alarm unit 24. The air pump and alarm unit 24 is hydraulically operated by means of water supplied thereto and air pressure originated in the air pump and alarm unit 24 leaves the pump through a pipe 27 which communicates with a drying filter 28 adapted to remove excess moisture from the air and which in turn communicates with the actuating device indicated by the numeral 21 by means of piping 29 which incorporates certain restricting devices known in the art. In order that an adequate supply of air under relatively low pressure may be available at all times, a reservoir 30 is placed in com-

munication with the air pump and alarm unit by way of a pipe 31 communicating with the pipe 27 the said reservoir 30 being, therefore, in communication with the actuating device 21 and the system of heat actuated devices 22 and pneumatic impulse conducting tubing 23.

The system of heat actuated devices 22 and the actuating mechanism 21 are so designed as to be capable of causing the unlatching of the clapper within the main valve 17 upon an increase of pressure occasioned by a rise of temperature adjacent one or more of the heat actuated devices 22. The automatic deluge sprinkler system is entirely dependent for its operation upon the system of thermally sensitive heat actuated devices 22, and the relatively low air pressure supplied to the heat actuated devices 22 is primarily, therefore, for supervisory purposes only as loss of that air pressure from the actuating system more rapidly than the reservoir 30 and the air pump 24 can replace it, will result in a dual signal being given, one signal being given by an electric trouble light 32 dependent in operation upon a pressure operated electric switch 33 which in turn communicates with the actuating device 21 and is adapted to energize the trouble light 32 upon a reduction of supervisory air pressure in the actuating system. The other one of the dual alarms is provided for in the construction of the air pump and alarm unit 24. It will, upon a loss of air pressure, open a valve establishing communication between the water supply pipe 25 and a pipe 34 which in turn is adapted to communicate with a water actuated siren or other hydraulically operated alarm means, not shown, but positioned at a point indicated by the numeral 35 in Figure 1.

In order to provide for the draining of the system comprising the riser 18 and pipes 19 after the system has been in operation, a valve 36 communicates with the main valve 17 and controls the communication thereof with a drain pipe 37. A drain pipe 38 communicates with the drain pipe 37 and leads from a funnel 39 adjacent the air pump and alarm unit 24. The funnel 39 is provided so as to be able to receive fluid overflowing from an L 40 which forms a part of the air pump and alarm unit 24. Water entering the air pump and alarm unit 24 through the water supply pipe 25 flows downwardly from the body member 24 into a main water leg 41 and upwardly through a secondary water leg 42 which in turn communicates with the L 40 at a point above the body 24 of the air pump and alarm unit. The secondary water leg 42 passes through the body member 24 and extends downwardly within the water leg 41 and terminates short of the bottom of the water leg 41.

By again referring to the gate valve 16 positioned on the supply pipe 15, it will be seen that a bonnet 43 thereon partially encloses a gate valve operating shaft 44 which in turn is provided with a hand wheel 45. The bonnet 43 has formed therein an alarm or monitor valve 46 which serves to cause an alarm to be given at such times as the gate valve 16 is closed or the hand wheel 42 thereof moved as in starting to close the same. This is accomplished by the opening of a fluid valve in the mechanism 46 which permits fluid to flow from the gate valve 16 through a pipe 47 which communicates with the pipe 34 previously described and which in turn extends to a remotely positioned fluid actuated siren, not shown, the remote position of which is indicated in Figure 1 by the numeral 35.

In order that dual alarms may be given at such times as the automatic deluge sprinkler system goes into operation in extinguishing a fire, a separate and distinct means is employed which comprises a remotely positioned fluid actuated siren or bell, not shown, the remote position of which is shown in Figure 1 by the numeral 48. The other of the dual signals comprises a pressure operated electrical switch 49 which may be obviously used to actuate any desirable electric signal. Both the pressure operated electric switch 49 and the remotely positioned fluid actuated siren 48 are placed in communication with the body of the main valve 17 by means of a pipe 50 which communicates with the body of the main valve 17 by way of a fitting 51.

In order to be certain that an alarm will be given upon the automatic deluge system's going into operation, still another separate and distinct alarm is provided which comprises an electric switch 52 which forms a part of the valve actuating device indicated at 21, the switch 52 as is fully illustrated in Figure 2 of the drawings and described more fully hereinafter, functions upon the actuation of the mechanism of the actuating device 21 and closes causing an electric circuit to be established through an electric bell 53 or other desirable signal. The switch 52 is also provided with a manual button so that an alarm may be originated therethrough or tests of the circuit made.

It will thus be seen that the automatic deluge sprinkler system comprises primarily the automatic or main valve 17 and its actuating device generally indicated at 21 and an air source for supplying air under pressure to a system of heat actuated devices 22 and that, therefore, the successful operation of the automatic deluge sprinkler system depends upon the satisfactory operation of the automatic or main valve 17.

By referring now to Figures 2 and 3 of the drawings, detailed illustrations of the valve 17 and its actuating device may be seen. By referring to Figure 2 in particular, it will be seen that the automatic or main valve 17 comprises the body member indicated by the numeral 17 in which a water inlet is indicated at 54. In order that the water inlet 54 may be effectively separated from the remainder of the valve body, an annular shoulder 55 provided with a seat ring 56 adapted to receive a clapper 57, serves to effectively control the admission of fluid into the valve body from the water inlet 54. A suitable rubber facing 58 is affixed to the clapper 57 by means of a clamping ring 59 which is in turn affixed to the clapper by means of a plurality of screws.

The clapper 57 is formed with a pair of hinge arms 60 adapted to pivot about a hinge pin 61 so as to effectively hinge the clapper in relation thereto. The hinge pin 61 is carried on suitable bushings positioned in the valve body 17. In order that the clapper 57 may remain in closed position on the fluid inlet 54 and thus prevent the passage of fluid through the valve, a latch mechanism is positioned within the valve body and adjacent to a shoulder 62 formed on the clapper 57. The latch mechanism comprises a latch 63 pivoted to the valve body by means of a latch hinge pin 64 so that horizontal movement toward the right imparted to the lower end of the latch 63 results in moving it from its seat on the shoulder 62 of the clapper 57, thus effectively releasing the clapper 57 and permitting fluid in the fluid inlet 54 to raise the

clapper 57 and flow through the valve into the riser 18. Still referring to the latch mechanism, it will be seen that a separate anti-reseating latch 65 is pivoted to the pivot 64 and adapted to prevent the clapper 57 from reseating. In order that the anti-reseating latch 65 will remain in effective operating position, a latch spring 66 is utilized which serves to position the anti-reseating latch 65 in operative relation to the clapper 57 at all times.

In order that movement may be imparted to this latch 63 so as to result in the opening of the clapper 57, a latch link 67 is pivoted at its inner-most end between a pair of extensions formed on the latch 63 by means of a link pin 68. This latch link 67 passes centrally through and is affixed to a circular latch link diaphragm 69 which is positioned in a water tight manner across an opening 70 in the valve body 17. The latch link 67 passes through an opening in the diaphragm 69 and is affixed therein in a water tight manner. A portion of the latch link extends outwardly therefrom and comprises in effect a T-headed connection section 71 adapted to receive in a movable manner a latch arm 72 which is part of the valve actuating mechanism 21 which comprises a vertically positioned actuating mechanism box bolted to the valve body 17 at a point thereon adjacent the opening 70 thereof so that its mechanism effectively imparts movement to the latch link 67. The latch arm 72 is pivoted by means of a hinge pin 73 to the box 21 and is adapted to impart movement to the latch link 67. In order that the latch arm 72 may receive movement suitable for actuating the latch link 67 and in turn the latch 63, an end 74 thereof is pivoted by means of a pin 75 to the lower-most end of a vertically positioned guide rod 76.

By referring to Figure 3 of the drawings, it will be seen that the upper-most end of this guide rod 76 is slidably positioned within a sleeve 77 which is in turn carried upon the vertically positioned box 21. By referring again to Figure 2 of the drawings, and to the lower-most portion of the actuating mechanism box 21, it will be seen that a bumper 78 is provided beneath the outer-most end of the latch arm 72 and that a secondary guide rod 79 is positioned vertically adjacent the guide rod 76. By referring now to Figure 3 of the drawings, it will be seen that an actuating weight 80 is positioned upon the guide rods 76 and 79 and is suspended in elevated relation thereon by means of a latch 81 which takes the form of a vertically positioned yieldable member and which is adapted to rest upon a protruding end of a supporting finger 82 thus holding the weight 80 in elevated position in the box 21 on the guide rods 76 and 79. The supporting finger 82 forms a part of a pressure responsive release mechanism 83 which pressure responsive release mechanism 83 comprises in part the subject matter of United States Patent No. 2,099,069 of November 16, 1937 to E. A. Lowe, et al.; wherein its complete structure and operating principles are adequately set forth. In order to simplify the present disclosure, this pressure responsive release mechanism 83 and its structure are not herein described, claimed, or illustrated as they are adequately set forth in the above mentioned patent and are therefore well-known in the art. In the present disclosure, an increase of air pressure, originated by the heat actuated devices 22, in the tubing 23 communicating with the valve actuating device

generally indicated at 21 in the drawings and in particular with the pressure responsive release mechanism 83 results in the movement of a pressure sensitive diaphragm in the pressure responsive release mechanism which permits a partial rotation of a milled shaft 84 which in turn permits a lever 85 to move and through a system of levers 86, 87, and 88 also permits a latch lever 89, which is formed with the supporting finger 82 thereon, to rotate about a pivot 90. In operation, as described in the above mentioned patent to Lowe and in the present device, the partial rotation of the latch lever 89 about the pivot 90 comprises the complete movement upon which the release of the weight 80 depends. In the present disclosure as is shown in Figure 3 the release mechanism 83 has been modified slightly with respect to the placement of certain external levers particularly as concerns the resetting levers thereof which have been moved to one side of the release mechanism 83 and in so doing a spring 91 has been substituted for a weight heretofore used to activate the lever shaft 86 of the mechanism. In order that the lever 85 may be moved to reset position as shown in dotted lines in Figure 3 an extended lever 91A has been positioned on the lever shaft 86 and arranged so that a reset finger 92 may be engaged therebeneath to elevate the extended lever 91A and reset the lever 85 with respect to the milled shaft 84 and thus permit the lever 87 to be retained beneath a keeper portion of the lever 85. The reset lever 92 extends outwardly through a flexible diaphragm 93 and terminates in a connection 94 which as is illustrated in Figure 3 has attached thereto a reset handle 95. A front elevation of this reset handle 95 is shown in detail in Figure 2 of the drawings. In operation the reset handle is moved downwardly which causes the inner-most end 92 of the reset lever to move the extended lever 91A upwardly and thus cause the lever 85 to move into reset position. By referring again to Figure 3 of the drawings, it will be seen that the tubular connection 23 enters a junction box 96 at the upper-most portion of the actuating mechanism 21 and passes downwardly therefrom into space beneath the pressure responsive release mechanism 83 where it terminates in a mercury check assembly generally indicated by the numeral 97. A description of the mercury checks and their mode of operation is not included in this disclosure as the same are essentially similar to a mercury check assembly set forth in the above mentioned Patent No. 2,099,069 in which a similar arrangement of mercury checks are illustrated, described, and claimed in connection with the pressure responsive release mechanism also set forth therein.

It will thus be seen that the rapid increase in temperature in fire zones protected by the automatic deluge sprinkler system will cause a pneumatic impulse to be originated by the heat actuated devices 22 which will be conveyed back to the valve actuating device 21 by means of the pneumatic impulse tubing 23. The impulse passing through the mercury checks 97, will reach the pressure responsive mechanism 83 through the tube 105 and cause the weight 80 to drop and unlatch the clapper 57 in the automatic valve 17. In order that an alarm may be given when the weight drops indicating that the system is definitely going into operation in extinguishing a fire, a bell or other signal 53 as shown in Figure 1 is electrically connected to the switch

box 52 forming a part of the valve actuating mechanism 21 and by referring to Figure 2 the switch 52 will be seen to comprise a mercury tube switch 115 positioned upon a tiltable bracket 116 which in turn is pivoted by means of a pin to a structural portion of the switch box enclosure 52A, an extension of the bracket 116 indicated by the numeral 117 is adapted to extend into position above the weight 80 in the adjacent portion of the valve actuating device 21 and to normally rest upon the weight 80 so as to hold the mercury switch 115 in open position as illustrated in Figure 2. It will thus be seen that at such time as the weight 80 drops, the bracket 116 will pivot upon the pin and cause the mercury switch 115 to be closed which will close a circuit through the bell or other signal 53. A manual switch 118 provided with a manual button 119 is also connected in the circuit so that a signal may be manually given if desired in connection with the manual actuation of the automatic valve 17 such as made possible by means of a manual pull 120 which is connected to a cable 121 as shown in Figures 2 and 3 of the drawings, the other end of the cable 121 being attached to a spring tensioned latch bar 122 which is vertically positioned adjacent the weight 80 and along side the supporting finger 82 of the pressure responsive release mechanism 83. As best shown in Figure 3 of the drawings, this latch bar 122 may be moved upwardly by the cable 121 and serve to move the bolt 81 off the supporting finger 82 by reason of an inclined portion 123 formed on the latch bar 122 coming into contact with the latch 81. In connection with this manual release, it will be obvious that extensions of the cable 121 could be carried over suitable pulleys and through suitable conduit to remote locations so that the automatic valve might be actuated manually if desired, as upon employees' observing the outbreak of a fire. Such manual operation would bring into full and positive action the automatic deluge sprinkler system and thus control the fire.

As the supervisory operation of this automatic deluge sprinkler system is dependent upon air pressure of approximately one and one-half (1½) pounds per square inch normally supplied the heat actuated devices and their communication system, the air pump and alarm unit generally indicated by the numeral 24 in Figure 1 forms an important part of the system as it cooperates with the automatic deluge sprinkler system particularly in the supplying of the necessary supervisory air pressure for the thermally sensitive system of heat actuated devices 22 and, in providing for a trouble alarm in the event of the loss of supervisory air from the same.

By again referring to Figure 1 of the drawings, it will be observed that the gate valve alarm 46 forms a portion of the gate valve 16 construction as it is formed as a part of the bonnet 43 adjacent that portion of the bonnet which engages the shaft 44 of the gate valve 16 at such times as the gate valve 16 is closed or an attempt is made to close the same, the fluid entering the body of the gate valve 16 flows into the alarm valve 46 and outwardly therefrom through the pipe 47 to the remotely positioned alarm. Thus any attempt to close the main gate valve 16 and thereby shut off the fluid supply source from the sprinkler system, will result in an immediate and positive alarm being given.

By referring now to Figure 4 of the drawings, a

modified form of the automatic valve 17 may be seen which comprises in effect an actual modification of the sprinkler system as a different actuating system is employed to actuate the modified form of automatic valve. In Figure 4 which is a side elevation similar in many respects to Figure 3 of the drawings heretofore described, an alarm valve body is indicated by the numeral 169 and is provided with an actuating mechanism 10 housing 170. The housing 170 conforms in general detail to the mechanism housing indicated by the numeral 21 in Figure 3, of the drawings herein and heretofore described with the exception that in the modification shown in Figure 4, only the upper-most portions of the housing are utilized. Positioned in a vertical portion of the housing 170, there are a pair of guide rods 171 and 172; guide rod 172 being comparable to the guide rod 16 heretofore described and the guide 171 being comparable to the guide rod 79 heretofore described. Positioned on these guide rods and movable vertically thereof, there is a weight 173 which again compares in exact detail with the weight 80 heretofore described. The weight 173 being suspended in elevated relation by means of a latch 174 which takes the form of a vertically positioned, yieldable member and is positioned on a protruding end of a supporting finger 175 thus holding the weight 173 in elevated position in the housing 171. The weight 173 is adapted upon falling, after being released by movement of the supporting finger 175, to strike mechanism comparable in exact detail with that shown in Figure 2 of the drawings and heretofore described, wherein the movement of a falling weight is used to unlatch the clapper 57 of the valve 17. In the present modification, the weight in falling strikes a latch arm 176 which in turn is engaged with a latch link and latch (not shown) which serve to hold the clapper (not shown) in normally closed position.

In order to permit the weight 173 to drop and thus release the clapper of the valve 169 and thus permit the entrance of fire extinguishing fluid to the automatic deluge sprinkler system's piping associated therewith, the riser of which is indicated by the numeral 177, an electrically actuated solenoid 178 is positioned in the housing 170, the actuating member thereof being indicated by the numeral 179, being positioned in operative relation to the lower end of a trigger member 180. The trigger member 180 is pivoted to the housing 170 by means of a pivot 181 and has a keeper portion 182 formed thereon which is adapted to retain partially thereinunder a bar 183 formed on an upwardly extending arm 184 which in turn forms a portion of the supporting finger structure 175, the whole of which is pivoted to the housing 170 by means of a pivot 185. Positioned in the housing 170 and above the construction just referred to there is a transformer and relay unit 186 to which power line connections 187 lead thus supplying a current source and to which circuit wires 188 lead which circuit wires 188 also engage the appropriate portions of a heat actuated electrical thermostat generally indicated by the numeral 189 which thermostat is capable of operation both upon fixed temperature and abnormal rate of rise temperature principles. The structure of the thermostat 189 is not herein further illustrated or described as the same comprises the subject matter of Patent #2,224,738 to E. A. Lowe et al. of Dec. 10, 1940, wherein the complete operating structure is adequately set forth and is, therefore, known in the art. In con-

nection with the present invention a plurality of such heat actuated thermostats 189 are positioned at spaced intervals; or spotted throughout the fire zones to be protected by the piping of the automatic deluge sprinkler system and the same will, upon subjection to either fusing temperature or an abnormal rate of rise of temperature, cause an electrical circuit to be closed which in the present invention actuates the relay 186 and thus energize the solenoid 178 as the same is connected thereto by means of wires 190. When this occurs, the actuating member 179 of the solenoid 178 moves away from the lower-most portion of the trigger member 180 thus permitting the trigger member 180 to swing to the right on the pivot 181 as it will be urged by the action of the weight 173 supported upon the supporting finger 175 which structure includes the arm 184 and the bar 183 which has been retained under the keeper 182 of the trigger member 180. Upon thus being released, the weight 173 falls and as heretofore described, causes the unlatching of the clapper of the automatic valve 169.

It will thus be seen that this modified form of the invention contemplates the provision of an alternate form of the automatic deluge sprinkler system in that the actuating portions of the system are entirely electrical. It will thus be seen that the preferred form of the invention as illustrated in Figures 1 through 3 of the drawings, has certain inherent advantages not found in the art. One of these advantages is the provision of dual signals being given as concerns the supervision effected of the thermally sensitive pneumatically operated heat actuated devices 22 and their system of pneumatic impulse conducting tubing. The system in its preferred form being entirely dependent upon the hydraulic pressure originating in its supply source is capable of operating entirely independent of any electric power source as both supervisory air pressure and alarm action are obtained through the inclusion in the system of the hydraulically operated air pump and alarm unit. In addition to these advantages the automatic deluge sprinkler system has the further advantage of insuring the giving of a positive electrical signal both on supervision of the thermally sensitive heat actuated devices and their systems and upon the system's, in general, going into operation in controlling a fire. Furthermore, hydraulic signals are given on both of these operations which insures the giving of adequate notice of the system's operation regardless of interrupted power conditions or other unforeseen accidents. As the automatic deluge sprinkler system is primarily intended for hazardous locations, it is important that the system always be in readiness for positive action and the system will adequately control fires originating in the areas in which it has been installed.

The automatic deluge sprinkler system provides for the actuation of the system in the event that fire is observed before the system goes into automatic operation and, therefore, provides an efficient and trouble free deluge sprinkler system

particularly adapted for hazardous locations wherein it will operate quickly and effectively in controlling fires.

Having thus described my invention, what I claim is:

1. In a fire extinguishing system having distributing pipes having open sprinklers thereon, a main valve having a clapper normally held in closed position by movable detent means and adapted to admit fluid to the distributing pipes when freed by movement of said detent means, a releasable actuating weight suspended above said detent means and cooperable therewith to free said clapper when released, a movable latch carried by said weight and engageable with a releasing member arranged to normally support said weight and operable to disengage said latch, electrical means for operating said releasing member, and independent means for freeing the latch to permit the weight to fall while the controlling releasing member is in position, said independent means for freeing the latch comprising a vertically disposed bar positioned adjacent the said movable latch and adapted to be moved vertically and having means adapted to disengage the said movable latch from the said releasing member so as to permit the weight to fall.
2. In a fire extinguishing deluge sprinkler system having distributing pipes having open sprinklers thereon, an automatic valve of the mechanical latch type having a clapper normally held in closed position by movable detent means and adapted to admit fluid to the distributing pipes when freed, means for moving said detent means so as to free the said clapper, said means including a releasable actuating weight suspended above the said detent means and cooperable therewith to free said clapper when released, a movable latch on said weight and engageable with a releasing member arranged to normally support said weight and operable to disengage said latch, independent means for releasing the said actuating weight to permit the weight to fall while the controlling releasing member is in supporting position, said independent means for freeing the latch comprising a vertically disposed bar positioned adjacent the said movable latch and adapted to be moved vertically and having means adapted to disengage the said movable latch from the said releasing member so as to permit the weight to fall.
3. In a fire extinguishing system, having distributing pipes having open sprinklers thereon, a main valve having a clapper normally held in closed position by movable detent means and adapted to admit fluid to the distributing pipes when freed by movement of said detent means, a releasable actuating weight suspended above said detent means and cooperable therewith to free said clapper when released, a movable latch carried by said weight and engageable with a releasing member arranged to normally support said weight and operable to disengage said latch, electrical means for operating said releasing member.

HARRY N. RIDER.
